UNITED STATES PATENT OFFICE.

FRANK DAVID BUTLER, OF TACOMA, WASHINGTON.

TURBINE.

Application filed November 26, 1927. Serial No. 235,919.

My invention relates to improvements in steam turbines and consists in the construction, combination and arrangement of parts herein described and then sought to be defined in the appended claims, reference being had to the accompanying drawings forming a part hereof and which show, merely for the purpose of illustrative disclosure, a preferred embodiment of my invention, it being understood that various changes may be made in practice, within the scope of the claims, without digressing from my inventive idea.

The object of my invention is to produce an efficient, compact, balanced, peripheral flow, pressure velocity compounded turbine.

With reference to the drawings, similar numerals represent and indicate similar parts in the several views, Figure 1 is a longitudinal section of a turbine embodiment which has rotor and stator buckets and is pressure velocity compounded according to my invention, the section being as would appear on the dotted line 1-1 of Figure 6; Figure 2 is an enlarged plan view of the face of one of the nozzle and reversing chamber stator sectors 11 which are further illustrated in Figures 1, 4, 5 and 6 in their relation to the rotor 1. The stator sectors 11 are preferably bronze castings provided with the progressive sizes of U-shaped high pressure reversing buckets 12, the low pressure reversing buckets 13 and the low pressure nozzles 14 cored in place during the moulding. The face of each stator sector is machined to a radius a trifle larger than the radius of the rotor, the U-shaped buckets 12 and 13, the low pressure nozzle 14 and the high pressure nozzle 15 are tangentially disposed in this curved face, the angle of said buckets from said face gradually increasing from the smallest high pressure bucket 12 to the largest low pressure bucket 13.

Figure 3 is an enlarged detail sectional view of the turbine parts illustrated in Figure 4 and as would appear on the dotted line 2-2 of that figure; and, Figure 6 is a partial end elevation and a broken away and transverse section of the turbine embodiment illustrated in Figure 1, which has rows of U shaped high and low pressure rotor and reversing buckets and is pressure velocity compounded as per my invention.

Referring to the symbols of the drawings, the numeral 1 indicates a built-up type of rotor consisting of a high pressure rotor bucket rim ring 2, a follower ring 3 and the follower ring securing bolts 4. The rim ring 2 is adapted to fit within the circular recess 5 of the rotor 1 and follower ring 3, and is pinched and held secure between

the former and latter when the bolts 4 are drawn up tight. The periphery of the rim ring 2 is provided with a series of tangentially disposed high pressure U-shaped buckets or deflecting surfaces 6, likewise the periphery of the rotor 1 and its follower ring 3 are provided with a series of tangentially disposed low pressure U-shaped buckets or deflecting surfaces 7, the smaller or high pressure buckets 6 being located in the center of the larger or low pressure buckets 7. The rotor 1 is secured to the shaft 8 which extends through the stuffing boxes 9 of the upper and lower halves of the turbine casing 10.

Figure 2 illustrates a plan view of the face of one of the nozzle and reversing chamber stator sectors 11 which are further illustrated in Figures 1, 4, 5 and 6 in their relation to the rotor 1. The stator sectors 11 are preferably bronze castings provided with the progressive sizes of U-shaped high pressure reversing buckets 12, the low pressure reversing buckets 13 and the low pressure nozzles 14 cored in place during the moulding. The face of each stator sector is machined to a radius a trifle larger than the radius of the rotor, the U-shaped buckets 12 and 13, the low pressure nozzle 14 and the high pressure nozzle 15 are tangentially disposed in this curved face, the angle of said buckets from said face gradually increasing from the smallest high pressure bucket 12 to the largest low pressure bucket 13.

In the operation of my invention steam is admitted to the chambers 16 and high pressure nozzles 15 of the stator sectors 11 from the steam supply connection 17 via the steam supply manifold 18 and nozzle control valves 19 and is directed by the annular juxtaposed diverging high pressure nozzles 15 to the series of U-shaped high pressure buckets 6 in the rotor 1. This initial jet of steam is deflected by and discharged, at a reduced velocity, from the U-shaped high pressure buckets 6 of the rotor into the smallest U-shaped high pressure reversing buckets 12 of the stator sectors 11. The steam entering the smallest buckets 12 of the stators 11, at a reduced velocity, is accelerated due to the fact that these buckets have a larger volume than the buckets 6 of the rotor and to the slight reduction in the steam pressure as it leaves the smaller and enters the larger buckets. The steam passing through the

smallest buckets 12 of the stators 11 is deflected and redirected in the buckets and re-enters the buckets 6 of the rotor thereby imparting a portion of the force of its velocity to said rotor and again suffering a reduction in velocity and as it is deflected and redirected in the buckets 6 of the rotor it enters the second smallest reversing buckets 12 of the stator sectors 11 and is again accelerated in velocity. This process of velocity compounding continuing as the steam passes to and from the series of high pressure reversing buckets 12 of the stators 11 and the series of high pressure rotor buckets 6 until it enters the low pressure nozzles 14 wherein it is deflected and redirected into the low pressure buckets 7 of the rotor 1 thereby being compounded in pressure.

The steam as it travels through the low pressure buckets 7 of the rotor 1 and the low pressure reversing buckets 13 of the stator sectors 11 continues to velocity compound similar to the manner in which it passed through the high pressure stage until it finally travels in a spiral flow beyond the largest low pressure reversing buckets 13 then via the exhaust space or compartment 20 and exhaust connection 21 of the turbine to the atmosphere or the condensing plant.

The ribs or partitions 22 of the low pressure reversing buckets 13 of the stator sectors cause a certain amount of the second stage or reduced pressure steam to velocity compound within the high pressure rotor buckets 6.

The high pressure rotor buckets 6 are milled at a smaller angle to the periphery of the rotor than the low pressure buckets 7, this being for the purpose of absorbing as much of the velocity of the steam as possible prior to its exhausting from the turbine rotor.

All rotor and reversing buckets are of less capacity at their centers than at their ends, this being for the purpose of preventing the steam from eddying as it passes through the centers of the buckets and is compressed due to its abrupt deflection.

The flat surfaces 23 around the high pressure nozzles 15 are for the purpose of preventing excessive steam leakage through the radial clearance spaces 24.

The holes for the securing bolts 25 and 26 of the stator sectors 11 are elongated to allow for adjusting the radial clearances of the stators.

Having thus described my invention, what I claim as new and desire to secure by Letters Patent is:—

1. In a turbine, a built up type of rotor consisting of a main body portion secured to the rotor shaft and having a quarter circular rim extending around its periphery, a follower ring having a quarter circular rim extending around its periphery and adapted

to be secured to the said body portion of said rotor, a semi-circular recess extending around the peripheries of the quarter circular rims of said main body portion and said follower ring at their intersection, a semi-circular rim ring adapted to fit in said recess and to be secured between the quarter circular rims of said main body portion and said follower ring, a series of U-shaped tangentially disposed high pressure buckets located in the periphery of said rim ring, a series of U-shaped tangentially disposed low pressure buckets located in the peripheries of the rims of said main body portion and said follower ring and extending beneath said rim ring.

2. In a turbine, a stator consisting of a flanged portion adapted to be bolted to the steam supply connection, an annular chamber having communication with said flanged portion and the steam supply thereto, a quadrant shaped portion having a face fitting close to the periphery of the turbine rotor, an annular diverging high pressure steam nozzle extending at an angle between said annular chamber and the face of said quadrant shaped portion, a series of U-shaped, tangentially disposed, gradually increasing sizes of high pressure reversing buckets located on the center line of the face of said quadrant shaped portion, the smallest of said buckets adjoining the large end of said high pressure nozzle, a wide smooth surface extending from the edges of said high pressure reversing buckets to the edges of the rotor face and a short distance from the heel of said high pressure nozzle, a series of U-shaped, tangentially disposed, gradually increasing sizes of low pressure reversing buckets located on the center line of the face of said quadrant shaped portion, the smallest of said low pressure reversing buckets being located the closest to the largest of said high pressure reversing buckets, a U-shaped, tangentially disposed, low pressure nozzle located to one side of the center line in the face of said quadrant shaped portion and between the largest of said U-shaped high pressure and the smallest of said U-shaped low pressure reversing buckets.

3. In a turbine, the combination of a rotor, a follower ring secured to and forming a part of said rotor, a semi-circular rim ring fitting and secured in a recess in the peripheries of and between said rotor and said follower ring, a series of U-shaped high pressure buckets tangentially disposed in the periphery of said rim ring, a series of U-shaped low pressure buckets tangentially disposed in the peripheries of said rotor and said follower ring and extending beneath said rim ring, a quadrant shaped stator conforming and being located adjacent to the periphery of said rotor and having tangentially disposed in the face thereof and

verging high pressure steam nozzle, a series of U-shaped high pressure reversing buckets of gradually increasing widths, a series of U-shaped low pressure reversing buckets of 5 gradually increasing widths, and, a U-shaped low pressure steam nozzle located between said series of U-shaped high and low pressure reversing buckets whereby the steam is caused to flow in a cyclonic peripheral course and to be pressure velocity compounded during its expansion.

4. In a turbine, a rotor having a series of U-shaped high pressure buckets tangentially disposed in the center line of the periphery thereof and a series of U-shaped low pressure buckets tangentially disposed in and being open at either end to the periphery thereof adjacent to the ends of said high pressure buckets, said low pressure buckets 20 circumscribing the outer partition walls of said high pressure buckets, the sectional area of the said low pressure buckets being less at their centers than at their ends, this being for the purpose of preventing the 25 steam from eddying as it passes through said centers of said low pressure buckets and is compressed due to its abrupt deflection.

5. In a turbine, the combination of a ro-

tor having a series of U-shaped low pressure buckets tangentially disposed in the 30 periphery thereof, said buckets circumscribing the outer partition walls of a series of U-shaped high pressure buckets similarly disposed, the angle of said low pressure buckets from the periphery of the rotor being 35 greater than the similar angle of the high pressure buckets, this larger bucket angle being for the purpose of absorbing as much of the velocity of the steam as possible prior to its exhausting from the the low pressure 40 buckets, a quadrant shaped stator conforming and being located adjacent to the periphery of said rotor and having tangentially disposed in the face thereof, a diverging high pressure steam nozzle, a series of U- 45 shaped high pressure reversing buckets, a series of U-shaped low pressure reversing buckets, and, a U-shaped low pressure steam nozzle located between said series of U- 50 shaped high and low-pressure reversing buckets, whereby the steam passing through said turbine is caused to flow in a cyclonic peripheral course and to be pressure velocity compounded during its expansion.

FRANK DAVID BUTLER.
